Primary Examiner — Wan Laymon*Assistant Examiner* — Clint A Samuel(74) *Attorney, Agent, or Firm* — Wegman, Hessler & Vanderburg(57) **CLAIM**

The ornamental design for a cutting blade, as shown and described.

DESCRIPTION

FIG. 1 is a perspective view of a cutting blade of the present invention;

FIG. 2 is a front elevation view thereof;

FIG. 3 is a rear elevation view thereof;

FIG. 4 is a right side elevation thereof;

FIG. 5 is a left side elevation view thereof;

FIG. 6 is a top view thereof; and,

FIG. 7 is a bottom view thereof.

The broken lines showing in the drawings are for the purpose of illustrating environmental structure and form no part of the claimed design.

1 Claim, 3 Drawing Sheets(56)
